(57) **CLAIM**

The ornamental design for a mobile medical diagnostic device, as shown and described.

DESCRIPTION

FIG. 1 is a perspective view of a mobile medical diagnostic device;

FIG. 2 is a front view thereof;

FIG. 3 is a rear view thereof;

FIG. 4 is a side view thereof;

FIG. 5 is another side view thereof;

FIG. 6 is a top view thereof; and,

FIG. 7 is a bottom view thereof.

The broken lines in the drawing views illustrate portion of the mobile medical diagnostic device that forms no part of the claimed design.
